UNITED STATES PATENT OFFICE.

WILLIAM H. WASHBURN, OF CHICAGO, ILLINOIS, ASSIGNOR TO FRANK S. SHAW, OF CHICAGO, ILLINOIS.

PROCESS OF MANUFACTURING LAMINATED VALVES.

1,415,745.

Specification of Letters Patent.

Patented May 9, 1922.

Application filed October 4, 1920. Serial No. 414,450.

To all whom it may concern:

Be it known that I, WILLIAM H. WASHBURN, a citizen of the United States, residing at Chicago, county of Cook, State of Illinois, have invented a certain new and useful Improvement in Processes of Manufacturing Laminated Valves, and declare the following to be a full, clear, and exact description of the same, such as will enable others skilled in the art to which it pertains to make and use the same, reference being had to the accompanying drawings, which form a part of this specification.

In Patent No. 1,338,759 granted May 4, 1920, I have illustrated a laminated valve built up out of thin washer-like discs of hard steel clamped between top and bottom holding plates and secured upon the end of a valve stem. The fastening together of the parts of the valve head and the union thereof with the stem is most conveniently secured by passing the valve stem through registering holes in the laminæ and the clamping plates, and riveting the stem over.

I have found that sometimes in valves made in this way the laminæ are not clamped together tightly enough to secure the full advantage of a perfectly made construction of the type disclosed in my aforesaid patent.

The object of the present invention is to produce a simple and novel method of building valves of the aforesaid type, in such a way that they will present the compactness and apparent rigidity at the periphery which is so desirable in such valves.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a view partly in section and partly in elevation through a set of dies in which are assembled the elements to form a single valve, the dies being open;

Fig. 2 is a view similar to Fig. 1, the upper die member being also shown in section, and the dies being partly closed on the work;

Fig. 3 is a view similar to Fig. 2, showing the dies fully closed on the work; and

Fig. 4 is a side elevation of one of the completed valves.

Referring to the drawing, 1 represents a lower die member in which is held a valve stem, 2, having thereon an annular shoulder, 3, located at some distance below the extreme upper end of the stem; the top of the shoulder being flush with the upper surface of the lower die member. On the neck, 4, of the valve stem, that is the part that extends upwardly from the shoulder, while the neck is hot, are placed in the order 60 named the lower follower or clamping plate, 5, the series of washer-like discs, 6, and the top clamping plate or follower, 7.

The upper die member, 8, carries a central riveting head, 9, which, when the dies 70 are closed upon each other, forges the projecting part of the neck 4 into a rivet head as indicated at 10 in Figs. 3 and 4. Surrounding the member 9 is a collar, 11, vertically slidable thereon; the collar being 75 provided with an annular flange, 12, through which pass loosely a plurality of bolts, 13, the upper ends of which are screwed into the upper die member; the bolts being long enough to permit the collar normally to project considerably below the lower end of the riveting head, 9. Between the flange on the collar and the overlying portion of the upper die are a series of strong compression springs, 14, which are put under an initial 80 compression when the parts of the machine are assembled.

The parts are so proportioned that when the upper die member is brought down, the yieldable collar engages with the upper 90 follower or clamping plate, 7, before the riveting head comes in contact with the part 4 of the valve stem which is to be riveted. Then, as the upper die member is lowered still farther, the group of washer-like parts 95 of which the valve is to be formed are pressed firmly together throughout a narrow marginal zone, the collar thereafter yielding and causing the springs to be further compressed. Not until after the parts of the 100 valve have been firmly clamped together along the margin does the riveting head begin its riveting operation or, at any rate, the riveting operation should not have progressed very far before the clamping of the 105 valve parts between the lower die and the yieldable collar has taken place. This intermediate condition is illustrated in Fig. 2 while in Fig. 3 the dies are shown completely closed, the riveting over of the projecting 110

end of the valve stem having been completed.

The top and bottom clamping plates out of which the valve is made are preferably of uniform thickness throughout so that a uniform distribution of pressure throughout the valve head will be secured in carrying out the steps of my process heretofore described. After the riveting operation has been completed, the valve head is machined so as to reduce the thickness of each of the two clamping or holding plates gradually to about the thickness of one of the individual laminæ at the peripheral valve face, 15; the finished lower and upper clamping plates being indicated at 5^a and 7^a in Fig. 4.

I claim:

1. The process of making a laminated valve which consists in inserting a valve stem through a series of laminæ lying be-

tween clamping plates applying pressure to said plates in the vicinity of their margins to press the laminæ firmly together, and then riveting said stem over.

2. The process of making a laminated valve which consists in firmly pressing together a stack of washer-like elements consisting of thick upper and lower clamping plates and thin intermediate laminæ, by means of pressure applied along the marginal portions of said plates forming a rivet out of a valve stem extending through the openings in said elements, and then machining said clamping plates to reduce the thickness thereof at the periphery to approximately that of the individual laminæ.

In testimony whereof, I sign this specification.

WILLIAM H. WASHBURNE.
